CLAIM

The ornamental design for a wall mounted frame for a wardrobe cabinet, as shown.

DESCRIPTION

FIG. 1 is a front perspective view of a wall mounted frame for a wardrobe cabinet showing our new design;
FIG. 2 is a top plan view on a reduced scale;
FIG. 3 is a side elevational view taken from the left in FIG. 1 and on a reduced scale; and
FIG. 4 is a rear elevational view of the wall mounted frame of FIG. 1 on a reduced scale.

FIG. 1

FIG. 4
